ECONOMIZER

George P. Jackson, Flushing, N. Y., assignor to
Combustion Engineering Company, Inc., New
York, N. Y., a corporation of Delaware

Application April 19, 1934, Serial No. 721,293

13 Claims. (Cl. 257—240)

This invention relates to economizers and has for its primary object the provision of efficient economizers of extremely simple and compact construction in which expansion difficulties are overcome.

More specifically, it is an object of my invention to provide an economizer employing headers into which the economizer tubes are connected in which the headers are arranged in a manner to simplify the construction of the economizer and to overcome expansion difficulties.

I propose to arrange the headers so that they will constitute a leakproof wall of the heating medium passage and thus eliminate the necessity of a tube sheet and make the entire length of the tubes available for heat transfer while at the same time making adequate provision for variations in expansion and contraction during operation of the economizer.

Another object resides in the provision of an economizer of the character described in which the economizer tubes and headers are supported from the casing in a novel manner.

A further object resides in increasing the heating surface of an economizer of the above character through the employment of fins on the economizer tubes.

How the foregoing together with such other objects and advantages as may hereinafter appear, or are incident to my invention, are realized, is illustrated in preferred form in the accompanying drawings, wherein—

Fig. 1 is a front view, partly in section, of an economizer constructed in accordance with my invention.

Fig. 2 is an end view of the economizer, the left hand half being in elevation, and the right hand half being in section on the line 2—2 of Fig. 1.

Fig. 3 is a fragmentary plan section taken on the line 3—3 of Fig. 1.

My improved economizer comprises in general, a casing A, of sheet metal construction suitably insulated as indicated at 4, and a plurality of economizer tubes B located within the casing.

The casing A is provided with an inlet and outlet for a heating medium such as flue gas, the inlet 5 being preferably located at the top, and the outlet 6 at the bottom of the casing. The end 7 of the casing is provided with insulated doors 8 giving access to the interior of the economizer.

The economizer tubes B are of U-bent form and the open or free ends thereof are connected into a plurality of headers 9 located at the end portion 7 of the casing.

The headers 9 are preferably of square cross section and are arranged in superposed relation with a slight space 10 between adjacent headers, which is filled with flexible packing material as indicated at 11.

The economizer tubes extend crosswise of the casing and are arranged in rows with the lower legs thereof connecting into the upper portion of the inner walls of the headers, and the upper legs thereof connecting into the lower portion of the inner walls of the adjacent headers so that circulation is from one header through the tubes to the next header, and so on until the fluid being heated has traversed all of the headers and tubes of the economizer.

In this instance, the lowermost header 9 is provided with a fluid inlet 12, and the uppermost header with a fluid outlet 13, so that flow of the fluid being heated is from the bottom to the top of the economizer, while the flow of the heating medium over the tubes is from top to bottom. Provision for a drain connection is made at 14 and for a relief valve at 15.

The headers 9 are supported in superposed slightly vertically spaced relation by support 25 from the casing A, comprising, in this instance, a plurality of vertically spaced supporting members 16 carried by the casing, and co-operating members 17 carried by the headers 9. The spacing of the members 16 is such that each header is individually or independently supported from the casing in slightly vertically spaced relation, and the supporting members 16 and co-operating members 17 are of such construction that the headers are free to move or slide in the direction 30 of the length of the tubes B. In the drawings, I have illustrated a very simple form of support in which the supporting members 16 carried by the casing are of angle form, as are also the co-operating members 17 carried by the headers, 40 the extending flanges of the members 17 being in sliding contact.

By thus individually or independently supporting the headers with freedom to move or slide, provision is made for taking care of variation in 45 expansion and contraction between the different elements of the economizer. For example, it will be seen that since each U-tube is connected into a pair of headers, the headers will move with respect to each other as expansion and contraction of the tube occur. In this connection it is to be noted that the fluid traversing the lower leg of each U-tube will be colder than the fluid traversing the upper leg, so that there is a differential expansion and contraction between 50 55

the legs of the tubes. Since the headers are spaced slightly apart vertically, there will be no friction between adjacent surfaces of the headers tending to prevent such movement. With reference to the flexible packing 11 which fills the spaces between headers, this will yield as relative movement of the headers takes place, but at the same time, provides a seal preventing leakage of heating medium past the headers.

10 In order to further insure against leakage past the headers, I have provided vertical seals 18 at the end portions of the headers, as will be seen from inspection of Figs. 1 and 3, in this instance comprising vertically extending angle members secured to the portions 20 of the casing and spaced slightly from the outer wall of the headers, with flexible or yieldable packing material 21 filling the space.

15 Referring to Fig. 3, it will be seen that the end portion 7 of the casing is somewhat wider than the remaining portion thereof in order to accommodate the end portions of the headers 9 and the supporting means therefor.

20 The economizer tubes B are supported from the casing at their looped ends by means of a plurality of vertically spaced supporting members 22 supported from the casing by means of vertically extending members 24. The members 22 are provided with spaced slots 25 for the reception of tabs 26 secured to the tubes as by means of welding. Thus a supporting arrangement is provided which enables free movement of the tubes relative to each other.

25 It will be seen from the foregoing, that I have provided a very simple and compact economizer in which tube sheets such as commonly employed in tube economizers, are eliminated because of the novel arrangement of the tubes and headers whereby the headers constitute a sealed end wall for the heating medium passage. Furthermore, by arranging the headers in close superposed relation, the economizer tubes are kept in relatively close spacing vertically of the economizer so that the vertical space is effectively used, and since no tube sheets are necessary, the entire length of the tubes is made available for heat transfer.

30 In order to further increase the heating surface of the economizer, I employ fins 27 on the tubes B. This is particularly advantageous in an economizer constructed in accordance with my invention because considerable heating surface is thereby added without the increase in weight which would result if a greater number of tubes and headers were added in order to obtain the additional heating surface, it being pointed out in this connection that in order to properly support such added weight, it would be necessary to make the casing of heavier construction.

35 I claim:

1. In an economizer, a plurality of headers, economizer tubes connected into said headers, means movably supporting the headers in superposed close proximity whereby they may move relatively to each other without friction therebetween, and sealing means between superposed headers.

2. In an economizer, a plurality of headers, economizer tubes connected into said headers, means movably supporting the headers in superposed but slightly vertically spaced relation, and sealing means for the spaces between headers.

3. In an economizer, a plurality of superposed headers, economizer tubes connected into said headers, means movably supporting said headers

independently of each other in slightly vertically spaced relation, and sealing means for the spaces between headers.

4. An economizer comprising in combination, a casing having inlet and outlet for a heating medium, economizer tubes within said casing, horizontally disposed superposed headers into which said tubes are connected, means individually supporting each header from the casing with the headers slightly spaced vertically, and means sealing the spaces between headers.

5. In an economizer, a plurality of horizontally disposed superposed headers, U-bent economizer tubes having their open ends connected into said headers, means movably supporting said headers independently of each other in slightly spaced relation, sealing means for the spaces between headers, and means movably supporting said U-bent tubes at their loop portions.

20 6. In an economizer, a plurality of horizontally disposed superposed headers, U-bent economizer tubes having their open ends connected into said headers, means movably supporting said headers independently of each other in slightly spaced relation, sealing means for the spaces between headers, and means movably supporting said U-bent tubes at their loop portions, said header supporting means comprising vertically spaced supporting members carried by the casing and co-operating members carried by the headers, and said tube supporting means comprising vertically spaced supporting members carried by the casing and co-operating members carried by the tubes.

35 7. An economizer comprising in combination, a casing having inlet and outlet for a heating medium, a plurality of U-bent tubes in said casing extending crosswise thereof, a plurality of horizontally disposed superposed headers at one wall of said casing into which the free ends of said tubes are connected, means individually supporting each header from the casing with the headers slightly spaced vertically, means supporting said tubes from the casing at their bent end portions, and means sealing the spaces between the headers.

40 8. An economizer comprising in combination, a casing having inlet and outlet for a heating medium, a plurality of U-bent tubes in said casing extending crosswise thereof, a plurality of horizontally disposed headers arranged in superposed but slightly vertically spaced relation, means individually supporting each header from the casing with freedom to move relative to its adjacent headers as expansion takes place in a direction lengthwise of the tubes, and means sealing the spaces between the headers.

45 9. An economizer comprising in combination, a casing having inlet and outlet for a heating medium, a plurality of U-bent tubes in said casing extending crosswise thereof, a plurality of horizontally disposed headers arranged in superposed but slightly vertically spaced relation, means individually supporting each header from the casing with freedom to move relative to its adjacent headers as expansion takes place in a direction lengthwise of the tubes, means supporting said tubes from the casing at the bent end portions with freedom to move as such expansion takes place, and means sealing the spaces between the headers.

50 10. An economizer comprising in combination, a casing having inlet and outlet for a heating medium, economizer tubes within said casing,

horizontally disposed superposed headers into which said tubes are connected, means at the end portions of said headers providing support for the headers from the casing independently of each other, in slightly spaced relation, and means sealing the space between headers.

11. An economizer comprising in combination, a casing having inlet and outlet for a heating medium, economizer tubes within said casing, horizontally disposed superposed headers into which said tubes are connected, a plurality of vertically spaced header supporting members carried by the casing, means carried by said headers engaging said supporting members, the spacing of said members being such that the headers are individually supported in close vertically spaced relation, and means for sealing the spaces between headers.

12. An economizer comprising in combination, a casing having inlet and outlet for a heating medium, a plurality of U-bent tubes in said cas-

ing extending crosswise thereof, a plurality of horizontally disposed superposed headers at one wall of said casing into which the free ends of said tubes are connected, means individually supporting each header from the casing with the headers slightly spaced vertically, means sealing the spaces between the headers and means supporting said tubes from the casing, including slotted supporting members carried by the casing, and vertical tabs carried by the tubes at 10 their bent portions fitting the slots in said supporting members.

13. An economizer comprising in combination, a casing having inlet and outlet for a heating medium, a plurality of superposed headers and 15 tubes connected thereto located within the casing, means supporting said headers and tubes from the casing, and fins secured to said tubes to increase the heating surface thereof.

20

GEORGE P. JACKSON.
